UNITED STATES PATENT OFFICE.

WILLIAM A. MYERS, OF RIVERSIDE, CALIFORNIA.

PRUNER'S COAT.

Original application filed March 20, 1920, Serial No. 367,550. Divided and this application filed January 26, 1921. Serial No. 440,080.

To all whom it may concern:

Be it known that I, WILLIAM A. MYERS, a citizen of the United States, and resident of Riverside, county of Riverside, California, have invented certain new and useful Improvements in Pruners' Coats, of which the following is a specification.

My invention relates to certain new and useful improvements in working garments, particularly coats or jumpers, adapted for wear and use in certain lines of work and more particularly wherein the worker is above or apart from the place where the tools are kept or located.

15 An important object of my invention is to provide a pocket construction for pruners' coats which will effectually prevent an accidental disengagement of a foldable pruner's saw therefrom when placed therein.

20 Another object is to provide a pocket construction which will effectually prevent the entrance of dirt, leaves, or other foreign material thereto.

A final object is to provide a pocket construction for the reception of a pruner's foldable saw, whereby the saw may be readily placed therein or removed therefrom, the pocket being suitably reinforced to resist wear, and to protect the wearer from contact with the teeth of the saw.

25 I accomplish the above objects by means of the construction herein described and illustrated in the accompanying drawings, in which:

30 Fig. 1 is a front elevation of a coat showing my improved tool holding pocket attached thereto.

35 Fig. 2 is a detail face view of my tool holding pocket showing a pruner's saw in place.

40 Fig. 3 is a transverse sectional view of my pocket taken on the line 3—3 of Fig. 2.

45 Referring more specifically to the drawings, my tool holding pocket construction 5 is shown as attached to a coat or jumper 6 of usual form, the pocket being preferably secured to the outer front face of the coat adjacent the left hand vertical edge in order that the wearer may readily insert or remove a tool therefrom. The bottom of pocket 5 is of a curvature adapted to conform to the configuration of a handle 7 of a foldable pruner's saw 8, as clearly shown in dotted lines in Fig. 2 of the drawings.

The upper transverse edge 9 of the pocket 5 is preferably reinforced by means of a strap or an additional strip of fabric 10, a number of folds or strips of fabric being interposed between one end of strip 10 and the outer face of coat 6, to form a stop or abutment 12, a rivet or other suitable securing means 13 passing therethrough, as clearly shown in the various figures of the drawings. Attached to the upper edge 9 of the pocket is an upwardly extending 65 blade protecting flap 14 being stitched or otherwise secured to the coat at two of its edges, 15 and 16, edge 17 being unsecured and forming an entrance to the pocket, as clearly shown in Figs. 1 and 2 of the drawings. Edge 17 of the flap is provided with a reinforcing strip 18 designed for the purpose of stiffening the edge and reinforcing the same; this reinforcing strip is extended down along the side and bottom of the 70 pocket, being suitably widened at the bottom in order to conform to the handle of the saw.

When a pruner's saw is folded, as clearly shown in Fig. 2 of the drawings, the butt 80 20 of the saw handle 7 will engage the lower edge of the abutment 12 and thus prevent an accidental displacement of the saw from the pocket. The blade 21 which may extend upwardly if not folded closely upon the 85 handle, is protected by the blade flap 14. By forming a protective flap for the blade of the saw it will be noted that the sleeve of the coat or jumper will not contact with the teeth of the saw, which would naturally 90 occur if such protective flap was not secured to the pocket construction. Also, by attaching the protective flap having a vertically disposed opening leading to the pocket all dirt, leaves, or other débris will be 95 prevented from entering the pocket, and the same will act as a guide when placing a folded saw within the pocket.

From the above description it will be apparent that I have provided a pocket construction for pruners' coats, whereby a foldable pruner's saw may be readily placed therein or removed therefrom, the pocket being of such a construction that when the saw is placed therein the teeth of the blade 105 will not contact with any other portion of the coat. Further, the stop formed at the entrance to the pocket will effectually pre-

23
vent the accidental displacement of the saw when the wearer of the coat is engaged in a pruning operation.

What I claim is:

5. 1. A coat provided with a pocket for a foldable saw, said pocket having an opening, a shouldered block of flexible material secured to the interior of the pocket near one end of the opening, said block of material 10 constituting a stop for the handle of the saw.
2. A coat provided with a pocket for a foldable saw, said pocket having an opening, a plurality of strips of material 15 secured to the interior of the pocket near one end of the opening forming a shouldered block, the lower edge of which constitutes a positive stop for the handle of the saw.
3. A coat provided with a pocket for a 20 foldable saw, said pocket comprising a lower portion having an opening, a plurality of layers of material secured to the interior of the said lower portion near one end of the opening and constituting a shouldered 25 stop for the handle of the saw and an up-

per pocket portion consisting of a flap extending upwardly from said first mentioned portion and secured along its top and one side edge to the coat, the remaining side portion being left unsecured to provide an 30 opening.

4. A coat provided with a pocket for a foldable saw, said pocket comprising a lower portion having an opening, a plurality of 35 layers of material secured to the interior of said lower portion near one end of the opening, said layers of material constituting a shouldered stop for the handle of the saw, an upper pocket portion consisting of a flap extending upwardly from said first mentioned portion and secured along its top edge and one side edge to the coat, the remaining side edge being left unsecured to provide an opening and reinforcing means 40 extending along the bottom of the pocket 45 and the edges of both of said openings.

Witness my name this 1st day of November, 1920.

WILLIAM A. MYERS.
